UNITED STATES PATENT OFFICE.

FERDINAND L. STEGER, OF STEGER, ILLINOIS, ASSIGNOR TO STEGER & SONS PIANO MANUFACTURING COMPANY, OF STEGER, ILLINOIS, A CORPORATION OF ILLINOIS.

DESIGN FOR A PHONOGRAPH-CABINET BODY AND LEGS.

54,472.

Specification for Design.

Patented Feb. 10, 1920.

Application filed August 11, 1917. Serial No. 185,789. Term of patent 7 years.

To all whom it may concern:

Be it known that I, FERDINAND L. STEGER, a citizen of the United States, residing at Steger, in the county of Cook and State of Illinois, have invented a new, original, and ornamental Design for a Phonograph-Cabinet Body and Legs, of which the following is a specification, reference being had to the accompanying drawings, forming a part thereof.

The drawing is a perspective view of a phonograph cabinet embodying this design.

The design is characterized by the general rectangular outline of the body and two rectangular panels in the front, each approximately square, but having the greater

dimension horizontal, the supports being corner legs of lathe-turned design, comprising each a relatively prominent lathe-turned feature near the junction of the upper end of the leg with the body.

I claim:

The design for a phonograph cabinet, body and legs, substantially as shown and described.

In testimony whereof, I have hereunto set my hand at Steger, Illinois, this 6th day of August, 1917.

FERDINAND L. STEGER.
